UNITED STATES PATENT OFFICE.

BENJAMIN F. CLICK, OF GRENOVA, KANSAS.

NUT-LOCK.

SPECIFICATION forming part of Letters Patent No. 252,647, dated January 24, 1882.

Application filed November 9, 1881. (No model.)

To all whom it may concern:

Be it known that I, BENJAMIN F. CLICK, a citizen of the United States, residing at Grenola, in the county of Elk and State of Kansas, have invented certain new and useful Improvements in Nut-Locks; and I do hereby declare that the following is a full, clear, and exact description of the same, reference being had to the annexed drawings, making a part 10 of this specification, and to the letters and figures of reference marked thereon.

Figure 1 of the drawings is a perspective view of my invention. Fig. 2 is a top plan view of the same with the sliding guard-plate removed, 15 and Fig. 3 is an elevation of the screw-bolt with screw-nut and its connections in section.

The present invention has relation to certain new and useful improvements in that class of nut-locks in which a spring connected to the 20 screw-nut is made to engage with a vertical groove in the screw-bolt to prevent the nut from being unscrewed.

The invention consists in the details of construction, substantially as shown in the drawings and hereinafter described.

In the accompanying drawings, A represents the screw-bolt of the ordinary construction, and B the nut, having the usual screw-threaded opening for the end of the bolt. The nut B 30 upon its upper surface has a depression or countersink, a, within which is located a spring-pawl, b. This pawl is bent so as to partially encircle a stationary pin, c, one end of said pawl bearing against a shoulder, d, while the 35 opposite end thereof engages with a suitably-formed groove, e, in the screw-bolt. The nut B is formed with a dovetailed recess, f, in which fits a correspondingly-formed dovetailed guard-plate, C. The recess f is slightly tapering, as 40 is also the plate C, so that the latter can be

placed in position at one end of the recess only, and when in place the opening in said plate will register with the opening in the nut B for the passage of the screw-threaded bolt A.

The grooves in the bolt A may be of any suitable form or constructed in such manner as to present a shoulder against which the end of the spring-pawl b abuts, so that the bolt can turn in one direction and be prevented from so doing in a reverse direction by the end of the 50 pawl engaging with the shoulder on the principle of the ordinary pawl and ratchet.

The spring-pawl b, in its construction, may be variously modified so long as its office is performed as above stated.

The guard-plate C being in position as shown in Fig. 1, the upper surface thereof is flush with the upper surface of the nut; and said plate has an opening, g, to admit the insertion of a suitable key to press back the end of the spring-pawl from contact with the shoulder of the 60 groove e, so that the nut can be unscrewed.

Having now fully described my invention, what I claim as new, and desire to secure by Letters Patent, is—

The combination, with the screw-bolt A, having a suitable shoulder or groove, e, of the screw-nut B, having connected thereto a suitable spring-pawl, b, said nut having a dovetailed recess, f, for the reception of the dovetailed guard-plate C, having opening g for the insertion of a key, substantially as and for the purpose specified.

In testimony that I claim the above I have hereunto subscribed my name in the presence 75 of two witnesses.

BENJAMIN F. CLICK.
